UNITED STATES PATENT OFFICE.

BERTRAM M. MILLS, OF PAWTUCKET, RHODE ISLAND.

HUMIDIFIER.

Application filed March 13, 1924. Serial No. 698,884.

To all whom it may concern:

Be it known that I, BERTRAM M. MILLS, a citizen of the United States of America, and resident of Pawtucket, in the county of Pawtucket and State of Rhode Island, have invented new and useful Improvements in Humidifiers, of which the following is a specification.

This invention relates to humidifiers or 10 atomizing devices employed for moistening the air in rooms or apartments, and more particularly to means for regulating such apparatus.

Humidifiers of portable type designed for 15 use in houses, offices, etc. are necessarily of small size and compact construction, and to meet the demands of the trade must be provided with motors of universal series wound type adapted to operate at high 20 speed under either direct or alternating electric current.

In one very efficient type of humidifier the water is atomized by means of a substantially horizontal disk rotating at high 25 speed, the water being contained in a shallow receptacle and fed to the disk by means of a conical boss depending into the liquid from the center of the disk, the water creeping up the sides of the boss under centrifugal action. While this type of humidifier is in general very satisfactory, it is observed 30 that as the water level in the container falls, the series motor tends to speed-up, due to the lessened resistance encountered by the conical boss. Such undue speeding of the motor is undesirable for several reasons, among which may be mentioned the non-uniform evolution of vapor from the device and the unpleasant noise or hum occasioned by the imperfectly balanced rotating parts running at excessive speed.

The object of the present invention is in general to improve humidifiers of the type referred to and more particularly to provide such humidifiers with means tending to maintain a uniform speed of the motor and other rotating parts regardless of the depth of liquid in the container or reservoir.

One mode of attaining the above object which has been chosen for specific illustration herein consists in providing the lower portion of the depending conical feed boss with one or more grooves, preferably spiral or helical, in its outer surface. These grooves are disposed at the lower end of

the conical boss and preferably become gradually shallower toward their upper ends. The provision of these grooves results in the maintenance of a substantially uniform load upon the motor irrespective of the position of the water level in the container, thus providing a substantially constant speed of operation with elimination of noise and the attainment of uniformity 65 in vapor output.

While the exact reason for this action which is observed to take place is not thoroughly understood, it is believed that when the grooves in the conical boss are 70 completely submerged they present comparatively little resistance to rotation, but as the water level falls and the grooves are gradually exposed they encounter resistance to rotation at the surface level of the water 75 due perhaps in part to the greater cohesion of the molecules of liquid at the surface, commonly referred to as "surface tension" and in part to the formation of waves or ripples upon the fluid surface, in either case requiring the expenditure of additional energy. Whatever the true theory of operation, the grooves herein described and illustrated constitute an exceedingly simple 80 and efficient means for attaining the desired object, but it is contemplated that other and equivalent means producing the same or analogous effects fall within the purview 85 of the invention.

In the accompanying drawings one specific embodiment of the invention has been chosen by way of example for illustration, and in the drawings:

Fig. 1 is a vertical diametral section through a humidifier embodying the present 90 invention;

Fig. 2 is a fragmentary side elevation of the lower end of the conical feed boss of the atomizer disk; and

Fig. 3 is a horizontal section on the line 100 3-3 of Fig. 1.

The present invention is illustrated as embodied in a humidifier of the general type disclosed in the application of Bertram M. Mills, Serial No. 670,257, filed October 23, 105 1923 to which application reference may be had for a more detailed disclosure of the operative parts of the humidifier proper.

In the drawings, the numeral 1 indicates a shallow receptacle for the water or other fluid to be atomized. This receptacle is provided with a flaring rim 2 having an

inwardly directed flange 3 constituting a support for a cover 4 whose lateral edges are flanged downwardly and rest upon the supporting member 3. The flanged depending edge of the cover 4 is slotted and bent to provide a series of atomizing vanes 4a.

The cover 4 forms a convenient support for a base member 5 upon which an electric motor 6 is supported. This motor is preferably of universal type adapted alternatively to operate under direct or alternating electric current. Such motor are usually series wound, at least in the sizes proper for use in portable humidifiers. Such series wound motors are well suited to use in a humidifier device of small size by reason of the high speeds which may thereby be obtained, but as the speed of such a motor varies inversely with the load it necessarily follows that if the load is unduly decreased the motor may race.

The shaft 7 of the motor extends downwardly through an opening in the plate 4 and the atomizing disk 8 is secured to the lower end of the shaft. This disk may be of any usual type, preferably having a substantially smooth lower surface from the center of which a conical boss 9 depends. While the term "conical" is employed as a convenient mode of designating the general shape of this boss it is to be understood that the term is used in a generic sense as including any device providing an upwardly and outwardly divergent peripheral surface, whether exterior or interior, and whether substantially straight or curved.

The peripheral surface of the boss 9 is provided with one or more grooves 10 extending upwardly from its lower end. As here shown three such grooves are provided, and these grooves extend helically or spirally about the axis of the boss. Preferably, although not necessarily, the grooves are deepest at their lower extremities, becoming gradually shallower toward their upper ends. In practice, it is found that the best results are obtained by terminating these grooves substantially at the mean water level although the exact extent of the grooves may be varied in accordance with their shape, the angle of convergence of the conical boss, and various other factors which will vary with the individual application of the invention. While it is preferred to employ the grooves here shown, it is contemplated that similar results may be obtained by the use of other means associated with the conical boss adapted to maintain a substantially uniform resistance to turning of the boss irrespective of the water level.

In operation, the motor 6 rapidly rotates the disk 8 and its boss 9 with the result that centrifugal action causes the water to creep up the peripheral surface of the boss onto the lower surface of the disk 8 upon which it

is drawn out into an exceedingly tenuous film and projected with great force against the vanes 5 so that it is completely broken up. When the receptacle 1 is substantially full the grooves 10 are entirely submerged and apparently offer but slight added resistance to the rotation of the conical boss 9 so that the speed of the device is but little reduced from that normally attained with an ungrooved boss and with the receptacle full. As the water level in the receptacle falls, the upper shallow ends of the grooves are first uncovered, thereby producing an increased resistance to rotation substantially sufficient to compensate for the decreased area of the boss remaining immersed in the water. As the water level continues to fall, the deeper portions of the grooves 10 are gradually exposed, such deeper portions providing a further increased resistance to turning, and this action progresses until the water level has fallen substantially to the lower end of the boss 10. In this way the motor encounters a substantially uniform resistance or load irrespective of the position of the water level in the container and thus the speed of the rotating parts does not vary substantially. The vapor output is thus uniform throughout the use of the device while all undesirable noise due to racing of the motor is eliminated.

I claim:

1. A portable humidifier comprising a fluid receptacle, an atomizing element, means for feeding fluid from the receptacle to the atomizing element, means for rotating the atomizing element, and means tending to vary the resistance of the atomizing element to rotation in inverse ratio to the height of the water level in the container.

2. A humidifier comprising a fluid receptacle, a rotary atomizing disk, a conical feed member depending from the center of the disk into the receptacle for feeding water from the latter to the disk, means for rotating the disk, and means associated with the conical member for maintaining a substantially constant resistance to rotation of the latter as the fluid level varies in the container.

3. A portable humidifier comprising a fluid receptacle, a rotary atomizing disk, a conical boss depending from the central part of the disk into fluid in the receptacle, an electric motor for rotating the disk and its boss, and means operative as the water level in the container descends to provide an increasing resistance to rotation directly proportional to the normal decrease in resistance due to the diminishing area of the boss immersed in the fluid.

4. A humidifier comprising a fluid receptacle, an atomizing element, a rotary conical feed member dipping into the fluid in the receptacle and adapted to feed water to the

atomizing element by centrifugal action, and an electric motor for rotating said conical feed member, said feed member having a groove in its peripheral surface extending upwardly from its lower end.

5. A humidifier comprising a fluid receptacle, a rotary atomizing disk, a conical feed boss depending from the center of the disk into the fluid in the receptacle, and an electric motor for driving the disk and its boss, the boss having a groove in its peripheral surface extending upwardly from its lower end, the groove being of diminishing depth

from its lower substantially to its upper extremity.

6. A humidifier comprising a fluid receptacle, a rotary atomizing disk provided with a conical depending feed boss depending from its center into the fluid in the receptacle, and means for rotating the disk and boss, the boss having a plurality of spaced helical grooves in its peripheral surface extending upwardly from its lower end.

Signed by me at Pawtucket, Rhode Island, this 7th day of March, 1924.

BERTRAM M. MILLS.
